ATTORNEY

UNITED STATES PATENT OFFICE.

DON G. ROY, OF TULSA, OKLAHOMA.

WELL-DEPTH REGISTER.

1,266,631.

Specification of Letters Patent. Patented May 21, 1918.

Application filed May 24, 1916. Serial No. 99,592.

To all whom it may concern:

Be it known that I, DON G. ROY, a citizen of the United States, residing at Tulsa, in the county of Tulsa and State of Oklahoma, have invented certain new and useful Improvements in Well-Depth Registers, of which the following is a specification.

This invention relates broadly to measuring implements, and more particularly, to 10 that class of measuring instruments whereby in the depth of oil-wells and the like may be ascertained by the workers.

It is also among the means and objects of 15 the invention, to provide a measuring instrument of the character stated, which is portable in nature, and one which may be readily attached to and detached from the drilling cable.

Another feature of the invention resides 20 in the novel construction and arrangement of the friction pulley which is adapted for engagement with the drilling cable, and of its connection with the register, whereby the latter will be operated to disclose the 25 exact depth of the well.

It is also among the primary objects of 30 the invention to provide a well depth measuring instrument which is of such simple construction as will reduce the cost of manufacture of constructions of this character, and provide novel details in the construction and arrangement of parts with view to 35 higher efficiency generally.

All of the foregoing together with additional advantageous details and arrangement of parts of the preferred embodiment 40 of my invention will be clear from the specific description hereinafter contained, when read in connection with the accompanying drawings forming a part hereof, wherein the said embodiment of the invention is illustrated for the purpose of facilitating a full understanding of the present 45 improvements.

45 In the drawings:—

Figure 1 is top plan of my improved device as applied to a fragment of the drilling cable, and

Fig. 2 is a transverse section taken on the 50 line 2—2 of Fig. 1.

Fig. 3 is a fragmentary section view through a portion of the registering mechanism.

Referring now more specifically to the 55 drawings, and in connection with which like reference numerals will refer to the same

parts in the several views, the drilling cable which carries upon the lower extremity thereof, the usual drilling implement, is designated by the numeral 1. With more 60 especial reference to the present improvements, I provide a supporting frame or body 2, which, has arranged adjacent its outer extremity, a register 3, whereby the revolutions of a friction wheel which will be hereinafter described, may be accurately registered thereby. Flanges 4 and 4 are formed adjacent the base portion of the register 3 and are provided with suitable openings 65 whereby screws 5 or other fastening devices 70 may be passed therethrough into engagement with the body 2 in order that the same may be secured thereto. A shaft 6 is arranged longitudinally of the body 2 and is supported for rotation thereupon within 75 concaved bearing grooves 7. A bearing 8 engageable over a portion of the shaft 6 is secured to the body portion 2, through the medium of bolts 9 which are passed through flanges formed upon the said bearing, which 80 bolts have turned into engagement with their threaded extremities, nuts 9'. A friction pulley 10 is mounted upon the shaft 6 at a point adjacent the outer extremity thereof and provides means whereby the 85 drilling cable 1 may be received thereby within a peripheral groove 11 as arranged therein. A plurality of handles, which I have designated by the numeral 12 are secured to one side of the body 2 and provide 90 means whereby the device may be supported by the operator in a position whereat the peripherally grooved friction pulley is engaged with the drilling rope 1. It is to be noted, that the longitudinally extending 95 shaft 6 extends into engagement with the register 3 and, upon rotation thereof, will serve to actuate the same.

By referring to Fig. 3, the section of the registering mechanism is clearly presented. 100 It will be seen that a sleeve 13 is mounted upon the shaft 6 and extends longitudinally through the casing of the register. This sleeve 13 is fixedly secured to one end of the casing, not being deemed necessary to be 105 herein shown, and is free of the shaft so as to allow this shaft 6 to rotate when the pulley 10 is rotated. Adjacent the outer end of the casing of the register the disk is fixed upon the shaft in any desired manner. This 110 disk is formed of a closed back 14 and a collar 15 formed thereon upon which the

reference numerals or characters are carried. It will be noted that the sleeve 13 terminates adjacent the inner surface of the back 14, thus permitting the disk to be turned as above specified. The next corresponding disk 15' is provided with a rack 19 which has a pinion 18 constantly meshing therewith. This pinion is carried upon the stub shaft 17 secured in any suitable manner to the sleeve 13. The lug 16 is formed upon the disk 14 while it should be understood that the remaining disks 15' are mounted on the sleeve 13. The sight openings 3' formed in the casing of the register are in alinement with the collar of the registering disk. As the shaft 6 rotates, the disk secured thereto will also be rotated and for this reason will move the lug 16. When this lug has moved one complete revolution it will engage the pinion 18 and will move the same a slight distance. As the pinion 18 is rotated it will rotate the next disk 15' by the meshing of the pinion with the rack 19. These disks are all similarly constructed, with the exception that only one disk is carried upon the shaft, while the remaining disks are mounted upon the sleeve and are also provided with the racks for the meshing engagement with the corresponding pinion. It is obvious that as the shaft rotates, the various disks will be rotated in order and with the corresponding rapidity to cause the indicating numerals or units thereof to be properly brought into alinement with the sight openings of the registering casing.

In reviewing the operation of the device, the drilling cable is engaged by the friction pulley 10 of the device, previous to its withdrawal from the well. The cable is then wound upon a suitable drum, whereby, the drilling tools may be elevated to the surface. The movement of the cable as caused by the winding thereof upon the drum, will cause the frictional pulley 10 to be rotated, which will, due to its connection with the shaft 6 cause that member in turn to actuate the registering mechanism of the register 3. Thus, it will be apparent, that should the pulley be one foot in circumference, the registering mechanism would be advanced one unit upon each complete revolution thereof, and thereby accurately measuring each foot of cable as it is passed over the frictional pulley upon its winding drum.

It should be noted that the handles 12 are fixedly mounted upon frame or body 2 and spaced from each other. Therefore the operator of the device may grip both handles for firmly holding the pulley 10 in engagement with the cable 1. If only one handle were used, it would not be possible for the operator to firmly hold the pulley in engagement with the cable, since the rapidly moving cable would tend to throw the pulley from engagement therewith, since one depending handle would act as a pivot element by turning in the operator's hand. Such pivotal action is prevented in applicant's device, since such pivot points are eliminated by the operator gripping both handles and holding the pulley in firm engagement with the cable, thereby positively registering the movement of the cable over the pulley.

I desire to have it understood, that the invention is not to be limited to the exact size of the friction pulley nor to the particular construction of the register, inasmuch as each of these elements may be changed or replaced as conditions or preference may dictate.

While I have herein disclosed a specific embodiment of the invention, it will be apparent to persons skilled in the art, that the invention is capable of embodiment in other forms and devices differing in detail and arrangement from that shown, as may be in keeping with the hereto appended claim.

Having thus described the invention, what is claimed is:—

A depth measuring device, including a rectangular elongated frame, a plurality of handles arranged at one side of the frame whereby the frame may be steadied, a rotatable shaft detachably mounted longitudinally on the frame, a cable engaging pulley on the shaft at one extremity thereof, and a check register having a casing provided with a sight opening secured to the frame at the other extremity thereof and connected with the remaining and adjacent end of the shaft whereby the units of the register will be moved into registration with the sight opening as the pulley is rotated.

In testimony whereof I affix my signature in presence of two witnesses.

DON G. ROY.
